UNITED STATES PATENT OFFICE.

ANTISTENE ABBAMONTE, OF CHEYENNE, WYOMING.

CYLINDER COCK.

Application filed May 2, 1924. Serial No. 710,607.

This invention relates to improvements in automatic cylinder drain cocks of the type employed in connection with steam engines for the purpose of draining the water of condensation from the cylinders and has reference more particularly to improvements in the valve described and claimed in U. S. Letters Patent 1,629,465, granted to me on May 24, 1927.

It is the object of this invention to produce a cylinder drain cock that will automatically open when the main throttle is closed so as to prevent any accumulation of water in the cylinder, and which automatically closes when the main throttle is open, so as to prevent the escape of steam when the engine is operated. It is the further object to produce a valve of this type that will automatically close when the engine is drifting so as to prevent cold air and dust from being sucked into the cylinder, and which shall be provided with means whereby the engine can move the same to open position while the engine is operating and while the engine is working with the throttle in fully open position.

Another object of my invention is to provide a cylinder cock of this type which shall have means associated therewith which will permit the valve to close at two different pressures. The object of this last named means is to permit the valve to close at a very low pressure during ordinary operation of the engine, but which will prevent the valve from closing until the pressure is at least twenty pounds per square inch during such times as the engine is standing idle in the roundhouse. This prevents the engine from moving if there is a considerable leak past the throttle valve, as sometimes is the case.

The above and other objects which may become apparent as the description proceeds are attained by means of a construction and an arrangement of parts which will now be described in detail, reference for this purpose being had to the accompanying drawing in which the preferred embodiment has been illustrated and in which:

Fig. 1 is a side elevation of my improved drain cock;

Fig. 2 is a longitudinal section taken on line 2—2, Fig. 1, and shows merely the cylindrical member from which the valves and end closures have been removed;

Fig. 3 is a longitudinal section taken on plane 3—3, Fig. 4, which is located at right angles to the plane on which Fig. 2 is taken; and

Fig. 4 is a section taken on line 4—4, Fig. 3. 60
 My invention comprises a hollow casing 5 which has an opening extending entirely through the same. This opening has several sections, all of which are cylindrical and which are of different diameters. Adjacent the upper end of the casing is a cylindrical section that has been indicated by reference numeral 6. This section has a plurality of spaced inwardly extending ribs 7, that serve as centering means for a valve 8 which is provided with a valve stem 9. Between the cylindrical section 6 and the cylindrical section 10 I have provided an inwardly projecting valve seat 11 that is adapted to cooperate with the valve seat 12 on the valve 8, 75 so as to form a steam tight closure. The cylindrical section 10 terminates in a short cylindrical section 13, which is of the proper size to receive the lower end of the valve stem 9 (see Fig. 3). A spring 14 surrounds the valve 80 stem and has one end abutting the shoulder 15 and the other abutting the underside of valve 8. This spring is under compression and tends to move the valve away from the valve seat. A plug 16 is provided with a 85 threaded portion 17 that engages the threaded section 18 in casing 5. This plug has an inwardly projecting conical member 19 that serves as a stop which limits the movement of the valve 8 away from the valve seat. 90 Casing 5 is also provided with a passageway 20 whose upper end 21 communicates with the cylindrical chamber 6 at a point between the valve 8 and the inner end of plug 16. The other end of this passage terminates in a threaded opening 22 which is adapted to be connected by means of suitable pipes to one end of the engine cylinder. 95

The casing member 5 has a cylindrical outwardly extending projection 23 which is hollow and which communicates with the cylindrical section 10. The opening 24 through the projection 23 serves as an exit for the steam or water which comes from the cylinder and which passes between the valve seats 11 and the valve. For the purpose of preventing air and dust from flowing inwardly through the opening 24 I have provided a cover 25 that is provided with a lateral extension 26 which is located between the two 105 110

2
lugs 27 and pivoted by means of a bolt 28 (Fig. 1). When there is a reduced pressure within the chamber 10, as when the engine is drifting, the valve 25 will close, so as to prevent air and dust from entering the cylinder.

The other end of the valve is provided with a cylindrical chamber 261 and is closed by means of a screw plug 271, which has a threaded portion that cooperates with the threads 281 in the end of the casing. The cylindrical portion 261 terminates in a valve seat 29 and communicates with the cylindrical section 30 which in turn communicates with a cylindrical section 31 of reduced diameter. A piston 32 is slidably mounted in the cylindrical chamber 261; this piston has a piston ring 33 that makes a close fit with the walls of the cylinder. This piston is also provided with a valve seat 34 that cooperates with the valve seat 29 so as to form an air tight seal when the piston is in the position shown in Fig. 3. The casing is also provided with an externally projecting boss 35 whose inner surface is threaded as indicated at 36. This boss is adapted to receive the end of a pipe, *a*, which extends to a three-way valve, *b* that controls air from the air supply *c* of the locomotive. A small opening 37 forms a communication between the interior of the boss and the interior of the cylinder 261. When compressed air is admitted into the cylindrical chamber 261, between the end of the piston and the plug 27, the piston will be moved upwardly until it seats against the valve seat 29, after the piston has seated no air can escape from one side of the piston to the other as it might do if the sealing action of the piston ring 33 were alone relied upon. The valve seat 29 and the corresponding surface 34 on the piston therefore serve the useful purpose of preventing the escape of air when this part of the valve is in operation. A stem 38 extends from the upper surface of the piston and terminates within the cylindrical chamber 31. This stem is provided with an annular flange 39 that serves to center the stem within the chamber 31. The parts are so adjusted that when the piston 32 is in the position shown in Fig. 3, valve 8 is held in open position. This valve can only close by moving the piston 34 downwardly until it seats against the inner end of the plug 271. This is taken advantage of for the purpose of increasing the pressure necessary to close the valve 8. The parts are so adjusted that when the piston 32 is seated against the plug 271 the valve 8 will close if it is subjected to a steam pressure of from two to three pounds, but when the parts are in the position shown in Fig. 3, it requires the pressure of from 20 to 25 pounds to move the valve 8 into closed position. This is due to the fact that when piston 32 occupies the position shown in Fig. 3, piston 8 cannot be moved towards closed

position without moving piston 32. The pressure of the ring 33 against the wall of the cylinder produces friction which must be overcome in addition to the force of the spring 14. Engineers are always required to 70 open the cylinder cocks when the engine is stopped for some time as, for example, when it is run into the roundhouse. When an engine is equipped with my valve, the engineer in moving the parts to open position, will 75 manipulate a three-way air valve so as to introduce air pressure into chamber 261. This moves the piston 32 against the seat 29 and when the air pressure is removed, it will remain in this position, until the valve 8 is 80 subjected to sufficient pressure to move against the resistance of the spring 14 and against the force due to the friction of the valve stem 9 and the friction of the piston ring 33 against the cylinder wall, which, as 85 above described, requires steam pressure of from twenty to twenty-five pounds, and therefore there is no danger of the valve 8 being moved to closed position on account of leakage as above pointed out. 90

Two of the automatic valves above described are used in connection with each engine cylinder, one valve being connected to the drain opening at each end of the cylinder, by means of a pipe which extends from the threaded opening 22 to the drain opening. An air pipe is connected to the threaded interior of boss 35 in the manner above explained. The threaded opening 22 has its axis located at right angles to the axis of the opening 24 so that the latter will normally lie in a horizontal position. The valve member 25 will normally rest lightly against the outer end of the projection 23 so that when the pressure on the inside is greater than atmospheric, steam is permitted to flow outwardly through the opening 24, but if the pressure within the chamber 10 is less than atmospheric valve member 25 will be moved against its seat and prevent air 100 from entering. When the engine is equipped as above described and when the engineer opens the throttle and permits steam to enter these cylinders, some of the steam will attempt to escape through the passage 22. The action of this steam is to close the valve 8 and to hold it in closed position as long as the pressure exceeds the minimum pressure of three pounds which is usually required for holding the valve in closed position. When the engineer closes the throttle, the pressure within the passageway 20 will be reduced to such an extent that the spring 14 will function to move the valves to open position. Any water of condensation will 110 now have a free passageway from the engine cylinder to the atmosphere, thus permitting the cylinders to drain. 115

When the throttle is closed while the engine is running, as, for example, in going 120

down a grade, the engine will act as an air pump and will reduce the pressure in passageway 20 to a point below atmospheric. Unless means are provided to prevent it, air and dust will be sucked into the cylinder at each stroke of the engine. To prevent this, the check valve 25 has been provided. If the engineer desires to open the cylinder cock while the engine is operating, he opens 10 a valve which permits air to flow into chamber 261 in the manner described.

Openings X and Y are provided in the casing above the piston 32 so as to prevent the upbuilding of a back pressure due to 15 leakage or otherwise.

From the above it will be apparent that I have produced a simple and substantial cylinder cock that is automatic in its operation and which serves not only to drain 20 the cylinders when the engine is inoperative, but which is provided with means to prevent cold air and dirt from entering the engine cylinder when the engine is drifting, and which is also provided with means for 25 conveniently opening the cylinder cocks when the engine is operating and for introducing an additional resistance against closing after an engine has been stopped.

Having described my invention what I 30 claim as new is:

1. In a cylinder drain valve, in combination, a hollow casing having an internal valve seat near one end, a valve provided with a valve seat adapted to cooperate with 35 the internal valve seat so as to close the opening, means comprising a spring for normally holding the valve away from its seat, said casing having a passageway adapted to be connected to the interior of a steam engine cylinder, said casing having also another opening which communicates with the atmosphere, said last named opening being located on the same side of the valve as the spring and on the side of the valve opposite 40 from the first mentioned opening and a check valve in the last named opening which permits an outward flow but prevents an inward flow.

2. In a cylinder drain valve, in combination, a hollow casing having an internal valve seat near one end, a valve provided with a valve seat adapted to cooperate with the internal valve seat so as to close the opening, means comprising a spring for normally holding the valve away from its seat, said casing having a passageway adapted to be connected to the interior of a steam engine cylinder, said casing having also another opening which communicates with the atmosphere, said last named opening being located on the same side as the valve spring and on the side of the valve opposite from the first mentioned opening, a check valve in the last named opening which permits an 45 outward flow but prevents an inward flow.

and means comprising a piston for exerting a force on the valve which acts in the same direction as the force exerted by the spring.

3. A cylinder drain cock comprising, in combination, a hollow casing having an 70 opening extending from one end to the other, means closing each of the end openings, an internal valve seat adjacent one end, a valve in the casing between the valve seat and the adjacent end closure, means for limiting the 75 movement of the valve away from the seat, said casing having a passageway opening into the interior thereof between the valve and the adjacent end closure, said passageway being adapted to be connected with the 80 interior of an engine cylinder, resilient means associated with the valve for normally holding it in open position and means for supplementing the force of the spring and for moving the valve to open position against 85 pressure.

4. A cylinder drain cock comprising, in combination, a hollow casing having an opening extending from one end to the other, means closing each of the end openings, an 90 internal valve seat adjacent one end, a valve in the casing between the valve seat and the adjacent end closure, means for limiting the movement of the valve away from the seat, said casing having a passageway opening 95 into the interior thereof between the valve and the adjacent end closure said passageway being adapted to be connected with the interior of an engine cylinder, resilient means associated with the valve for normally holding it in open position and means for supplementing the force of the spring and for moving the valve to open position against 100 pressure, said last named means comprising a piston adapted to be moved in one direction by means of compressed air and means associated with the piston for engaging and moving the valve.

5. A cylinder drain cock comprising, in combination, a hollow casing having an opening extending from one end to the other thereof, plugs closing the openings in the ends, the inner surface of said casing being provided with two valve seats, one near each end closure, a valve member mounted for movement 110 in one end of the casing between the one valve seat and the end closure, a stop for limiting the movement of the valve away from the seat, resilient means comprising a spring for normally holding the valve 115 against the stop, a piston located in the other end between the other valve seat and the end closure, said piston having a surface adapted to cooperate with the valve seat to form a seal, said casing having an opening that communicates with the space between the end of the piston and the end closure and means associated with the piston for moving the valve from its seat when the piston is moved 120 towards its seat.

6. A cylinder drain cock comprising, in combination, a hollow casing having an opening extending from one end to the other thereof, plugs closing the openings in the ends, the inner surface of said casing being provided with two valve seats, one near each end closure, a valve member mounted for movement in one end of the casing between the valve seat and the end closure, a stop for limiting the movement of the valve away from the seat, resilient means comprising a spring for normally holding the valve against the stop, a piston located in the other end between the valve seat and the end closure, said piston having a surface adapted to cooperate with the valve seat to form a seal, said casing having an opening that communicates with the space between the end of the piston and the end closure, means associated with the piston for moving the valve from its seat when the piston is moved towards its seat, and means for preventing air to flow inwardly past the piston when the latter is in open position.

7. An automatic drain valve of the class described, comprising, in combination, a casing having two chambers connected by a passageway, means closing the ends of said chambers, each of said chambers having valve seats, a valve member located in one of said chambers between the valve seat and the end closure, means comprising a spring for normally holding the valve away from its seat, said casing having a passageway one end of which is in communication with the chamber containing the valve and the other end of which is open to the atmosphere and adapted to be connected with the interior of an engine cylinder, a piston slidably mounted in the other chamber between the valve seat and the end closure and means associated with the piston for moving the valve towards open position when the piston moves towards the valve seat with which it cooperates.

8. An automatic drain valve of the class described, comprising, in combination, a casing having two chambers connected by a passageway, means closing the ends of said chambers, each of said chambers having valve seats, a valve member located in one of said chambers between the valve seat and the end closure, means comprising a spring for normally holding the valve away from its seat, said casing having a passageway one end of which is in communication with

the chamber containing the valve and the other end of which is open to the atmosphere and adapted to be connected with the interior of an engine cylinder, a piston slidably mounted in the other chamber between the valve seat and the end closure, means associated with the piston for moving the valve towards open position when the piston moves towards the valve seat with which it cooperates, and means for preventing the flow of a fluid past the valve and into the passageway when the valve is in open position.

9. A cylinder drain cock comprising a casing having a chamber whose walls is formed with a conical surface forming a valve seat, means for closing one end of said chamber, a valve located in the chamber between the valve seat and the end closure, said casing having a passageway, one end of which is in communication with the chamber between the end closure and the valve, said casing having also an outlet which communicates with the chamber on the side of the valve seat opposite the end closure, means comprising a spring for normally holding the valve member away from the valve seat and means for supplementing the force exerted by the spring with a frictional resistance that must be overcome before the valve can be moved against the seat.

10. A cylinder drain cock comprising a casing having a chamber whose wall is formed with a conical surface forming a valve seat, means for closing one end of said chamber, a valve located in the chamber between the valve seat and the end closure, said casing having a passageway one end of which is in communication with the chamber between the end closure and the valve, means comprising a spring for moving the valve towards the end closure for opposing a force to any closing movement of the valve and means for adding a force that opposes the movement of the valve from open towards closed position, said casing having an outlet opening located on the side of the valve opposite from the end closure and means for closing said opening when the pressure within the chamber is less than atmospheric.

In testimony that I claim the foregoing as my own, I have hereto affixed my signature.

ANTISTENE ABBAMONTE.
